COMBINATION SOAP HOLDER AND GRAB BAR

Don Schreckengost, East Liverpool, Ohio, assignor to Federal Ceramics Corporation, Mineral City, Ohio, a corporation of Ohio

Filed Apr. 16, 1962, Ser. No. 69,719

Term of patent 14 years

(Cl. D4—3)

FIG. 1 is an isometric view of a combination soap holder and grab bar embodying my new design;

FIG. 2 is a top plan view thereof;

FIG. 3 is a front elevational view;

FIG. 4 is a side view thereof.

FIG. 5 is a rear elevational view on a reduced scale. The side not shown is like the side shown.

I claim:

The ornamental design for a combination soap holder and grab bar, as shown and described.
